UNITED STATES PATENT OFFICE.

CHARLES LEHRFELD, OF NEWARK, NEW JERSEY.

COMBINED TELEPHONE RECEIVER AND PHONOGRAPH REPRODUCER.

Application filed June 20, 1924 Serial No. 721,154.

To all whom it may concern:

Be it known that I, CHARLES LEHRFELD, a citizen of the United States, residing at Newark, in the county of Essex and State 5 of New Jersey, have invented certain new and useful Improvements in Combined Telephone Receivers and Phonograph Reproducers; and I do hereby declare the following to be a full, clear, and exact description 10 of the invention, such as will enable others skilled in the art to which it appertains to make and use the same, reference being had to the accompanying drawings, and to characters of reference marked thereon, which 15 form a part of this specification.

This invention relates, generally, to a novel combined telephone receiver and phonograph reproducer adapted to provide a convenient device whereby a phonograph 20 reproducer with its amplifying horn element may also be utilized as a loud speaker in connection with wireless telephone receiving sets, all in such manner that the device may function as a sound reproducer 25 common to both a phonograph instrument and a radio receiving set, and may be selectively used at will to function in connection with the phonograph elements or with the radio elements without change or necessity 30 for manipulation or alteration in either case.

The invention has for its principal object to provide a simple and convenient sound reproducer to serve in common with both a phonograph instrument and a radio receiving 35 set; and the invention has for a further object to provide in a single instrument or device, having a single sound reproducing diaphragm, an electro-magnetic means for vibrating said sound reproducing diaphragm and a mechanical means for also 40 vibrating said sound reproducing diaphragm.

The invention has for a further object to provide a novel means for adjusting the 45 electro-magnetic means relative to the sound reproducing diaphragm without interfering with or in any way disturbing the fixed connection and relation of the mechanical diaphragm vibrating means relative to said 50 diaphragm.

Other objects of this invention, not at this 55 time more particularly enumerated, will be clearly understood from the following detailed description of the same.

With the various objects of this invention

in view, the same consists, primarily, in the novel combined telephone receiver and phonograph reproducer hereinafter set forth; and, the invention consists, furthermore, in the novel arrangements and combinations of the various devices and parts, as well as in the details of the construction of the same, all of which will be more fully described in the following specification, and then finally embodied in the claims appended thereto.

The invention is clearly illustrated in the accompanying drawings, in which:—

Figure 1 is a front face view of the novel combined telephone receiver and phonograph reproducer made according to and embodying the principles of this invention; Figure 2 is a rear face view of the same; Figure 3 is a front face view of the same with the cover plate and diaphragm removed; Figure 4 is a side elevation of the same; Figure 5 is a transverse section, taken on line 5—5 in Figure 1; Figure 6 is another transverse section, taken on line 6—6 in Figure 1; and Figure 7 is a rear face view 80 of the cover plate and diaphragm, showing also the mechanical means for vibrating the latter, when used as a phonograph reproducer.

Similar characters of reference are employed in all of the hereinabove described views, to indicate corresponding parts.

Referring now to said drawings, the reference character 8 indicates the main casing of the novel combined telephone receiver and phonograph reproducer, the same having an open forward side and a back-wall 9 to close its rear side. The open side of said casing 8 is provided with an outwardly projected annular marginal flange 95 10. The reference character 11 indicates a cover-plate provided with a central opening 12 surrounded at its outer end with a forwardly projecting throat flange 13, whereby a union with a tone-arm and amplifying 100 horn (not shown) may be effected. Said cover plate 11 is provided in its rear face with a counter-sunk seat 14 for the reception of a suitable sound reproducing diaphragm 15. Said sound reproducing diaphragm 105 may be made of mica or any other suitable material. In assembling the diaphragm with the casing and cover plate, so that the same extends across the open side of the casing, I prefer to employ a suitable keeper 110

ring or washer 16, which overlaps the marginal edge portions of the diaphragm, to thus retain and bind the latter in the seat 14 of the cover plate, the outer portions of 5 said keeper ring or washer 16 being clamped intermediate the outer marginal portions of the cover plate and the marginal flange 10 of the casing, when the cover plate is secured to said flange 10 by the fastening 10 screws 17.

The electro-magnetic means for vibrating the sound reproducing diaphragm 15 comprises the following mechanism. Disposed within the interior chamber 18 provided by 15 the casing 8 is a carrier plate 19 preferably made of a rigid insulating material such, e. g. as bakelite. Molded into said carrier plate 19, or otherwise suitably affixed thereto, so as to project rearwardly therefrom, is 20 a threaded shank 20. Said threaded shank 20 projects exteriorly from said casing 8 through a central opening 21 provided in the back wall 9. A spring element 20' is interposed between the back-wall 9 of said 25 casing 8 and the rear face of said carrier plate 19, the tension of which normally presses said carrier plate forwardly toward the diaphragm 15. Threaded upon the exteriorly projecting end of said shank 20 is 30 an adjusting nut 22, which is provided at its inner end with a chambered portion 23. Secured upon said shank 20, within said chambered portion 23 of the nut 22, are lock-nuts 24, which, when properly positioned and locked on said shank, serve as a stop for limiting the outward or rearward movement of the shank and carrier plate, when the shank is actuated in outward direction by the adjusting nut 22. The free 40 end of the shank 20 is provided with an enlarged head 25, suitably secured thereto, which serves as a stop for limiting the inward or forward movement of the shank and carrier plate, when the shank is actuated in inward direction by the adjusting nut 22. Supported upon the outer or forward face of said carrier plate 19 are a pair of magnetic core pieces 26 and 27 of opposite polarity, which are aligned diametrically 45 upon the carrier plate, and which respectively possess at their free ends right angled outward extensions 26' and 27', upon which are respectively mounted electro-magnetic coil windings 28 and 29. Permanent magnets 50 30 and 31 are also associated with said core pieces 26 and 27, the same being each of semi-circular form, and so disposed relatively to the core pieces, that the respective positive poles of said permanent magnets 55 will overlap and couple with the one core piece 26 to produce a positive polarity as to said core piece 26, while the respective negative poles of said permanent magnets will 60 overlap and couple with the other core piece 27 to produce a negative polarity as to said core piece 27. Said core-pieces 26 and 27 and the permanent magnets 30 and 31 are both secured to said carrier plate 19 and retained in the above described operative assembled relation, by means of fastening 70 screws 32 which extend upwardly through the carrier plate and respective core-pieces, to screw into keeper clips 33 which bridge the adjacent opposed ends of the permanent magnets 30 and 31, so as to both retain the 75 same in place and also bind the same respectively in connection with the respective core-pieces. In order not to interfere with or disturb the polarity of the permanent magnets, said keeper clips are made of any suitable rigid non-magnetic material, such, for example, as brass or other non-magnetic metal. The electro-magnetic coil windings 80 28 and 29 are connected in series, and suitable binding posts 34 and 35 are provided to receive the attachment of their free terminal wires, and at the same time serve to connect the conductors 36 and 37 leading from and to a radio receiving set (not shown), whereby the electro-magnetic means 85 for vibrating the diaphragm 15 may be actuated by the electrical impulses transmitted from the said radio receiving set. Said binding posts 34 and 35, may be mounted in connection with said core-pieces as shown, 90 but if so, are insulated from electrical engagement therewith by insulation bushings 38. The casing is provided with a suitably disposed opening 39 in its side wall for the admission of said conductors 36 and 37. Secured centrally to the inner or rear face of said diaphragm 15, in any suitable manner, as, e. g. by cementing or otherwise, is an armature piece 40, preferably consisting of 95 a disc of soft iron, which is opposed to the ends of the core-pieces 26' and 27' and subject to the attraction and repulsion thereof. 100 Since the above described electro-magnetic means for vibrating the diaphragm 15 is supported upon the carrier-plate 19, and 105 since the carrier plate is arranged for movement toward or away from the diaphragm, it is possible to delicately adjust the electro-magnetic means relative to the diaphragm 110 so that the most effective cooperation between the same may be easily maintained. If, e. g., it is desired to adjust the electro-magnetic means toward the diaphragm, the 115 adjusting nut 22 is backed upon the shank 20, with the result that the spring element 20' will thrust the carrier plate forward; if, however, it is desired to withdraw the electro-magnetic means away from the diaphragm, the adjusting nut 22 is turned inwardly upon the shank 20, thus forcibly 120 drawing back the carrier plate against the tension of the spring element 20'. 125 The means for mechanically vibrating the diaphragm 15, through the agency of a phonograph record, comprises a suitable ful-

erum bracket 41 which projects radially from the circumference of said cover plate 11, and which is, preferably, integrally formed in connection therewith. Said bracket is so constructed as to provide a pair of laterally spaced and rearwardly off-set side-pieces 42, in which are adjustably supported inwardly directed and opposed pivot studs 43 which serve as a fulcrum for a stylus lever 44. The inner arm 45 of said stylus lever 44 extends inwardly, through an opening 46 in the side wall of said casing 8, into the interior of said casing; the same passing between the electro-magnetic coil windings 28 and 29. The inner extremity of said arm 45 is provided with a forwardly turned substantially right angled extension or terminal member 47 which engages and is permanently secured to the rear side of the diaphragm 15 by attachment to the center of the armature piece 40. The outer end of said stylus lever 44 is formed to provide a stylus or needle receiving socket piece 48, in which the usual phonograph stylus or needle 49 is operatively mounted and secured by a set screw 50 in the usual manner. It will be apparent that when the stylus or needle 49 is engaged by a rotated phonograph record, the stylus lever 44 will be oscillated on its fulcrum to thereby produce mechanically induced sound reproducing vibrations of the diaphragm 15.

From the above description it will be quite evident that my above-described invention provides a very compact simple and convenient sound reproducing device, by means of which the sound reproduction may be produced mechanically through the agency of the usual phonograph mechanism, or electrically through the agency of electrical impulses transmitted by a radio receiving set, so that a common sound reproducing diaphragm may be selectively actuated by either method at will, without necessitating any "change-over" manipulations or alterations of either position or arrangement of the sound reproducing device or any of its parts.

Having thus described my invention, I claim —

1. In a sound reproducing device, a casing open at its forward side, a diaphragm secured across the open side of said casing, an oscillatable stylus lever, means to fulcrum said stylus lever, the inner arm of said stylus lever being secured centrally to said diaphragm, electro-magnetic devices supported within said casing behind said diaphragm and respectively on opposite sides of said stylus lever, and said diaphragm having an armature piece connected with its rear face in opposition to said electro-magnetic devices, all whereby said diaphragm may be selectively actuated by either said stylus lever or said electro-magnetic devices.

2. In a sound reproducing device, a casing open at its forward side, a diaphragm secured across the open side of said casing, an oscillatable stylus lever, means to fulcrum said stylus lever, the inner arm of said stylus lever being secured centrally to said diaphragm, electro-magnetic devices supported within said casing behind said diaphragm and respectively on opposite sides of said stylus lever, said diaphragm having an armature piece connected with its rear face in opposition to said electro-magnetic devices, all whereby said diaphragm may be selectively actuated by either said stylus lever or said electro-magnetic devices, and means for adjusting said electro-magnetic devices toward or away from said diaphragm.

3. In a sound reproducing device, a casing open at its forward side, a diaphragm secured across the open side of said casing, an oscillatable stylus lever, means to fulcrum said stylus lever, the inner arm of said stylus lever being secured centrally to said diaphragm, electro-magnetic devices of opposite polarity supported within said casing behind said diaphragm and respectively on opposite sides of said stylus lever, said diaphragm having an armature piece connected with its rear face in opposition to said electro-magnetic devices, all whereby said diaphragm may be selectively actuated by either said stylus lever or said electro-magnetic devices, and means for adjusting said electro-magnetic devices toward or away from said diaphragm, comprising a movable supporting plate upon which said electro-magnetic devices are secured, said supporting plate having a rearwardly extending threaded shank projecting exteriorly through the rear wall of said casing, spring means for normally thrusting said supporting plate forward toward said diaphragm, and an adjusting nut threaded upon the exterior end of said shank to produce longitudinal movement of the latter in either direction.

4. In a sound reproducing device, a casing open at its forward side, a diaphragm secured across the open side of said casing, an oscillatable stylus lever, means to fulcrum said stylus lever, the inner arm of said stylus lever being secured centrally to said diaphragm, electro-magnetic devices of opposite polarity supported within said casing behind said diaphragm and respectively on opposite sides of said stylus lever, said diaphragm having an armature piece connected with its rear face in opposition to said electro-magnetic devices, all whereby said diaphragm may be selectively actuated by either said stylus lever or said electro-magnetic devices, and means for adjusting said electro-magnetic devices toward or away from said diaphragm, comprising a

4
movable supporting plate upon which said electro-magnetic devices are secured, said supporting plate having a rearwardly extending threaded shank projecting exten-
5 sively through the rear wall of said casing, spring means for normally thrusting said supporting plate forward toward said dia- phragm, an adjusting nut threaded upon the exterior end of said shank to produce

longitudinal movement of the latter in 10 either direction, and stop devices for limiting the movement of said shank in either direction.

In testimony, that I claim the invention set forth above I have hereunto set my hand 15 this 12th day of June, 1924.

CHARLES LEHRFELD.
